DESIGN FOR A MOMENTUM WRENCH

Raymond L. Stoyer, Lebanon, Pa.

Application August 7, 1947, Serial No. 140,758

Term of patent 14 years

(Cl. D54—13)

To all whom it may concern:

Be it known that I, Raymond L. Stoyer, a citizen of the United States of America, residing at Lebanon, in the county of Lebanon and State of Pennsylvania, have invented a new, original, and ornamental Design for a Momentum Wrench, of which the following is a specification, reference being had to the accompanying drawing, forming a part thereof, wherein:

Fig. 1 is a side elevational view of a momentum wrench, showing my new design,

Fig. 2 is a top plan view,

Fig. 3 is a front elevational view, and

Fig. 4 is a rear elevational view.

I claim:

The ornamental design for a momentum wrench, as shown.

RAYMOND L. STOYER.
